ROTARY SNAP ACTION MECHANISM

Christian E. Buerki and Harold L. Mekelburg,
Milwaukee, Wis., assignors to Cutler-Hammer
Inc., Milwaukee, Wis., a corporation of Delaware

Application December 10, 1945, Serial No. 634,058

7 Claims. (Cl. 74—112)

1

This invention relates to a rotary snap action mechanism. Although not limited thereto the mechanism is particularly well adapted for operation of electric circuit controllers of the drum type.

An object of the invention is to provide a rotary snap action mechanism which is unusually rugged and durable in construction and not likely to get out of order.

Another object is to provide such a mechanism wherein the necessity for overtravel of the manual operating member in moving the drum from each position thereof to another is eliminated.

Another object is to provide a novel form of latching wheel, to be rigidly attached to the driven shaft, and a pair of locking pawls to be associated therewith.

Another object is to so construct and arrange the pair of pawls as to insure positive stopping of the latch wheel in its next succeeding position by the inactive pawl as an incident to unlocking of the latch wheel through the medium of an associated star wheel.

Another object is to provide for rotary movement of a driven element from a given position to substantially any desired number of other positions by merely increasing the number of notches in the latch wheel and by correspondingly increasing the number of projections on the star wheel.

Another object is to so construct and arrange the pair of pawls as to insure against locking of the mechanism in any given rotary position thereof in the event of breakage or other failure of the driving spring.

Another object is to provide novel means for insuring return of each of the pawls to normal position after each operation of the snap action mechanism.

Other objects and advantages of the invention will hereinafter appear.

The accompanying drawings illustrate a preferred embodiment of the invention which will now be described, it being understood that the embodiment illustrated is susceptible of modification in respect of certain structural details thereof within the scope of the appended claims.

In the drawings: Figure 1 is a fragmentary horizontal sectional view of the fixed portion of a drum controller casing, showing in top plan (and in dotted lines) most of the elements of our improved rotary snap action mechanism; the polygonal portion of the driving shaft being shown in section.

Fig. 2 is a fragmentary side elevation (viewed

as indicated by the arrows 2—2 in Fig. 1) showing the construction and manner of pivotally supporting the pair of latching pawls.

Fig. 3 is a fragmentary vertical sectional view, on the line 3—3 of Fig. 1; the casing cover, and bearing parts for both the driving and driven shafts being also illustrated, and

Fig. 4 is a fragmentary top plan view, in separated relation, of the pawls shown in Fig. 2; the pivot portion of the pin being shown in transverse cross section.

Referring to Fig. 1 of the drawings, the numeral 10 designates the fixed portion (usually a metal casting) of a casing adapted to house or enclose a circuit controlling drum of any suitable or well known form having our improved snap action operating mechanism associated therewith. Portion 10 preferably has perforated lugs 11 and 12 formed integrally with and projecting laterally from the respective side edges of the bottom wall 13 adjacent the rear end of the latter; similar perforated lugs (not shown) being also preferably provided at the forward corners of said bottom wall. Said lugs serve the usual purpose of providing for attachment of the housing by bolts or screws to a floor or similar support. A one piece removable housing member (not shown) of substantially U-shape in horizontal cross section is adapted to fit between the bottom flange or surface 14, 14 and the cover portion 15 (see Fig. 3); any well known means being provided for attaching said removable housing member to portion 10.

Cover portion 15 is provided with a relatively large circular opening 16 (Fig. 3) surrounded by an upstanding flange 17, to which a metal member 18 is attached (preferably removably) by any suitable means (not shown). Member 18 is provided with a centrally located circular opening 19 surrounded by an upwardly extending flange 20 and a downwardly extending flange 21. Flange 21 is provided with an annular recess 22 of rectangular form in transverse cross section opening to the lower face thereof and communicating with the opening 19. Said recess is adapted to accommodate a unit comprising a pair of annular metal members 23 and 24, the adjacent inner edges of which are completely grooved to provide a substantially semicircular ball-race for partial accommodation of the usual series of balls 25. The other half of the ball-race is formed by providing an annular groove 26 of substantially semicircular form in the periphery of a circular metal member 27, which is of a size to be freely rotatable within opening 19.

The members 23 and 24 are assembled with respect to member 27, with the balls 25 interposed therebetween; after which a relatively thin metal member 28 is formed thereabout as shown to retain said parts in assembled relation. Member 27 is provided with a centrally located opening 29 of polygonal form in transverse cross section (herein shown as square) to accommodate with a rather close fit the upper end portion 30, of corresponding shape in transverse cross section, of the driving shaft of the device.

Said driving shaft is provided with a relatively long intermediate cylindrical portion 31, and a slightly reduced cylindrical lower end portion 32; a shoulder 33 being thus provided between portions 31 and 32.

The driven shaft of the device is designated by the numeral 34; only the upper end portion of said shaft being illustrated. Shaft 34 is shown as of square form in transverse cross section, to facilitate attachment of the usual segments or contacts in a well known manner; it being understood that said shaft is of sufficient length to accommodate the required or desired number of movable contacts (not shown) to afford the desired circuit controlling characteristics; the required number of stationary contacts on one or both sides of shaft 34 being likewise provided. The dotted line rectangle 34^a in Fig. 3 is a dia-grammatic representation of the drum composed of the aforementioned stationary and movable contacts.

The driven, or drum, shaft 34 is rotatably supported within the housing in any suitable manner; the same preferably having ball type bearings at or adjacent the upper and lower ends thereof; one of the bearings being shown at 35 in Fig. 3, and the same being substantially like the bearing unit (23, 24, 25, 27, 28 for the upper end portion 30 of the driving shaft) afore-described. The metal block associated with driven shaft 34 and forming a part of the bearing 35 is designated by numeral 36.

A metal ratchet or latch wheel 37 having an integral hub 38 projecting downwardly therefrom has an opening 39 therethrough; said opening being of square form in transverse cross section to slidably fit over the correspondingly shaped upper end of shaft 34. Hub 38 is provided at one point with a threaded opening 40 to accommodate the shank of a set screw 41, which when tightened is adapted to rigidly connect wheel 37 to shaft 34; a split lock-washer 42 and a lock-nut 43 preferably being associated with set screw 41 to prevent accidental loosening thereof. In practice we prefer to provide two tapped openings 40 arranged at right angles to each other, and a corresponding number of set screws 41. Latch wheel 37 is provided in its upper surface with a centrally located countersink or recess 44 to provide a seat for the ball-bearing unit of known form, consisting of complementary outer elements 45 and 46, an inner element 47, and the usual set of balls 48. The reduced lower end 32 of the driving shaft fits within the circular opening in the inner element 47; the aforementioned shoulder 33 being adapted to seat against the upper surface of element 47 (Fig. 3).

A latch-tripping (or pawl-tripping) star-wheel 49 surrounds the lower end of the intermediate cylindrical portion 31 of the driving shaft; a tubular member 50 composed of self-lubricating bearing material being preferably interposed between wheel 49 and said driving shaft. Wheel 49 as shown overlies the aforementioned elements

45 and 47 of the ball-bearing unit to retain the latter in proper position.

A transversely divided metal spool composed of like upper and lower portions 52, 53 has said portions strung upon the intermediate cylindrical portion 31 of the driving shaft; said portions being adapted to jointly accommodate a multiple-coil torsion spring 53, the outwardly extending end portions of which are designated by numerals 54 and 55. Spool portions 52, 53 are interposed between the hub 51 of wheel 49 and a metal block 56 having a square opening 57 therethrough to accommodate the lower end portion of the correspondingly shaped portion 30 of the driving shaft. One end 58 extends laterally a substantial distance beyond the spool portions 52, 53 and is provided with an opening 59 to accommodate with a press fit a relatively long metal pin 60 which projects downwardly from member 56. As shown pin 60 is preferably of cylindrical form and opening 59 is correspondingly of circular form in transverse cross section. When pin 60 has been pressed into the opening 59, as shown in Fig. 3, said parts are preferably "tack" welded to each other at the peripheral line designated by numeral 61 in Figs. 1 and 3.

A second, but somewhat longer, pin 62 is provided; the same having a press fit within an opening 63 extending through the aforementioned wheel 37 and projecting upwardly from the latter, as best illustrated in Fig. 3. Pin 62 is likewise preferably tack welded to wheel 37 along the peripheral line designated by numeral 64 (Fig. 3). As shown in Figs. 1 and 3 both of the pins 60 and 62 are overlapped by the spring ends 54 and 55 on opposite sides thereof respectively. As shown in Figs. 1 and 3, wheel 49 is provided with an arcuate slot 65 to afford clearance between the same and pin 62. The peripheral contours of the respective wheels 49 and 37 is best illustrated in Fig. 1. Thus, the latch wheel 37 is shown as having six peripheral notches 37^a, 37^b, 37^c, 37^d, 37^e and 37^f. The portions of said notches hidden from view by wheel 49 are indicated by dash lines in Fig. 1.

The latch-release or star-wheel 49 is provided with six double-inclined cam projections respectively designated 49^a, 49^b, 49^c, 49^d, 49^e and 49^f. Like relatively short pins 66^a and 66^b (preferably of cylindrical form) are rigidly attached to the respective projections 49^f and 49^a and project upwardly therefrom for selective engagement by the lower end of pin 60, according to the direction of rotation of driving shaft 30, as by means of the usual manual operating handle (not shown). In practice we prefer to provide the projections 49^f and 49^a with circular openings to accommodate reduced portions or shanks formed on pins 66^a and 66^b, the ends of which shanks are upset over the lower surface of wheel 49, as shown at 66^c in Fig. 3.

A bracket 67 has a horizontal portion 67^a attached to the lower surface of cover member 15 in any suitable manner, as by means of a pair of bolts 68, 69 and nuts 68^a, 69^a; a downwardly offset horizontal portion 67^b of said bracket having an opening 67^c to accommodate the upper reduced end portion 69^a of a pivot pin; said end portion being upset as shown at 69^b (Fig. 3) to secure the pin to said bracket. The relatively large intermediate portion 69^c of said pin is surrounded by the coils of a torsion spring 70 whose end portions or extensions 70^a and 70^b are normally biased into engagement with opposite sides respectively of a pair of studs or pins 71 and 72;

the pin 71 having a shank portion riveted to the aforementioned bracket portion 67^b, as shown at 71^a (Figs. 1 and 3), and the pin 72 having a shank riveted to the lower surface of a metal plate 73, as shown at 72^a in Fig. 3. Plate 73 is rigidly and permanently attached, as by fusion welding, to an upper machined metal member 74, which is preferably of square form in transverse cross section as illustrated in Fig. 4; three-fourths of the lower surface area thereof being cut away, or offset upwardly to provide a substantially triangular projection or stop portion, as indicated in dotted lines at 74^a in Fig. 4. A second metal member 74 (of the same form as that aforementioned) is shown at the right-hand side of Fig. 4, said second member being reversed endwise, so that the projection 74^a is adapted to cooperate with the first member to limit clockwise movement of the upper member 74 and counterclockwise movement of the lower member 74. The members 74 having openings 74^b therethrough to freely accommodate a tubular bearing member 75^a formed of a suitable bearing metal or alloy. Bearing member 75^a is freely slidable onto the reduced pivot portion 69^d of the aforementioned pin; said pivot portion 69^d having a transverse opening therethrough adjacent its lower end to accommodate a cotter pin 76 or the like, whereby members 74, 74 and 75^a are held in assembled relation thereto. A pair of metal pawls 77 and 78 (which may be bent in reverse directions as illustrated from identical blanks) have portions 77^a and 78^a, respectively, of reduced width fusion welded or otherwise rigidly attached to members 74 in the relative positions shown in Figs. 1 to 4. The latching end portions 77^b and 78^b of pawls 77 and 78 have opposite faces located in parallel planes approximately radial to the axial center of driven shaft 34; said end portions preferably having double-inclined edge portions designated by numerals 77^c and 78^c (Fig. 1).

A pair of like sheet metal members have portions 79^a and 80^a thereof spot-welded or otherwise rigidly attached to the adjacent portions 77^d and 78^d of pawls 77 and 78; the aforementioned members having integral portions 79^b and 80^b bent as shown to lie in substantially parallel planes in the normal positions of the parts, as shown in Fig. 1. Portions 79^b and 80^b are preferably provided with cylindrical bosses 79^c and 80^c, Figs. 1, 3 and 4, which act to center and retain the opposite ends of a relatively heavy coiled compression spring 81, whereby the pawls 77 and 78 are biased to the normal positions thereof shown in Fig. 1. The spring 81 is adapted to provide for movement of either of the pawls 77 or 78 relatively to the other in the event of breakage or other failure of the main torsion spring 53, to thereby insure against locking or binding of said pawls with respect to the wheels 37 and 49 of the snap action mechanism, as hereinafter more fully described.

As shown in Fig. 3, the ball bearing associated with the upper end portion of driven shaft 34 is supported by a bracket member 82, which may be attached in any suitable manner to the part 10 of the drum housing. Bracket 82 is provided with an opening 82^a to provide rotary clearance for the part 36 of said bearing. The metal shell 83 which retains the outer elements of the bearing in assembled relationship to each other is preferably welded or otherwise rigidly attached to a surrounding plate or annulus 84, which is in turn rigidly attached to bracket 82.

As shown in Figs. 1 and 3, member 56 and por-

tion 30 of the driving shaft are provided with openings extending transversely therethrough to accommodate with a drive fit a tapered pin 85, whereby member 56 is restrained against movement axially of the driving shaft.

With the parts of the snap action mechanism constructed and arranged as aforescribed, the driving shaft 30 may be rotated continuously in either direction to provide for snap movement of 10 the driven shaft (and the movable drum contacts or segments carried thereby) through a total range of twelve different positions spaced thirty degrees apart. In practice, at least one of said positions will be an "off" position of the drum. 15 If it is desired to limit rotary movement of the drum in opposite directions through a maximum range of eleven different positions, a suitable stop member such as that shown in dotted lines at 86 in Fig. 1 may be rigidly attached to a part (such as block 56) which is rotatable with the driving shaft 30; stop 86 being adapted to cooperate with a suitable stop such as that shown in dotted lines at 87 in Fig. 1.

Stop 87 is preferably rigidly attached to the 25 stationary part 10 of the drum housing, as illustrated. With such an arrangement the drum cylinder, represented by driven shaft 34, may be rotated with a snap action to eleven different positions spaced thirty degrees apart. Thus if it 30 be assumed that the stationary and movable contacts of the drum are arranged to provide for "off" positioning of the drum parts in the respective positions of the parts of the snap action mechanism shown in Fig. 1, then upon clockwise rotation of driving shaft 30 the drum parts may be made to assume in sequence ten other rotary positions, all of which may be "on" positions to provide for commutation of a circuit to be controlled, or any number of which may likewise be "off," or 40 circuit interrupting, positions.

By suitably widening stop member 87, or by adding a second stationary stop member such as that shown in dotted lines at 88 in Fig. 1, the total number of different rotary positions to which the 45 drum cylinder may be moved in sequence with a snap action is reduced to ten.

If the drum is of the reversing type, the parts as illustrated may be assumed to be in "off" position, and stops such as those shown at 87 and 88 may be properly positioned to provide for movement of the drum cylinder with a snap action in either direction to five (or less than five) different "on" positions; it being obvious that the drum would be required to be returned to said "off" position before being rotated in a direction to provide the reverse connections afforded by such drum. The stationary and movable contacts of the drum and the stop members may be arranged in various different ways common to the drum controller art, depending upon the particular circuit controlling functions desired.

The operation of the snap action mechanism is as follows: Assuming the drum parts to be in "off" position, upon clockwise movement of driving shaft 30, as by means of a suitable manually operable handle attached thereto, the pin 60 will move the projecting end 55 of torsion spring 53 to store energy in the latter. The end 54 of said spring will tend to move with pin 60, but will be restrained by engagement thereof with pin 62, which is attached to the latch wheel 37; the latter being locked against clockwise rotation by engagement of the lower shoulder of notch 37^e (Fig. 1), which is initially quite closely adjacent thereto, with the latching end portion 77^b of pawl 77.

Pin 60 continues in a clockwise direction until it engages the relatively short pin 66^b on star wheel 49, whereupon the latter is likewise positively driven in a clockwise direction. Such clockwise movement of wheel 49 results in engagement of the left-hand inclined edge or cam surface of projection 49^d with the end 77^c of pawl 77 to rotate the latter out of the notch 37^e.

When pawl 77 has been rotated sufficiently to provide clearance for the outer edge of the portion 37^e interposed between notches 37^d and 37^e the wheel 37 will move with a snap action, under the bias afforded by spring 53, until the right-hand shoulder of notch 37^c is engaged with the other pawl 78, as indicated by the dotted line position of the portion 37^h interposed between notches 37^b and 37^c in Fig. 1. It is to be understood that during the aforementioned rotating or releasing movement of pawl 77 the pawl 78 will be tilted further into the notch 37^e, whereby stopping of latch wheel 37 after rotation thereof through an angle of thirty degrees is positively insured.

If rotation of driving shaft 30 is discontinued the elements of the snap action mechanism will assume the relative positions illustrated (in part) in dotted lines at 37^h, 49^b and 37ⁱ, 49^c in Fig. 1.

If, however, clockwise rotation of driving shaft 30 is continued, the left-hand inclined edge or cam surface of projection 49^b will engage the end 78^c of pawl 78 (which is still positioned within notch 37^e, but with the right-hand shoulder of the latter adjacent said pawl, as indicated in dotted lines in Fig. 1), and upon lifting of pawl 78 until it clears the outer edge of portion 37^h (located between notches 37^b and 37^c) the wheel 37 will again be moved clockwise with a snap action until the right-hand shoulder of notch 37ⁱ (note dotted line showing of portion 37ⁱ in Fig. 1) engages the pawl 77, whose end is then positioned within notch 37^d. The aforementioned lifting of pawl 78 acts in the manner aforescribed to temporarily tilt pawl 77 inwardly against the normal bias of spring 78, for the purpose aforescribed.

Inasmuch as the driven shaft 34 is rigidly connected with wheel 37 it follows that snap movement of the drum 34^a to each of its various positions is likewise effected through the medium of the energy thus stored in torsion spring 53, which is of such size or caliber as to afford the necessary torque or power.

Clockwise rotation of driving shaft 30 may thus be continued through one or more complete revolutions thereof (in the absence of any stops such as 86, 87); and as will be apparent, the snap action mechanism acts in a substantially similar manner (but in reverse relationship to the parts of wheels 37 and 49) upon counterclockwise rotation of driving shaft 30.

As will be apparent from the foregoing description, the spring 53 acts to bias wheel 49 to the normal position relatively to wheel 37 and relatively to block 56 as shown in full lines in Fig. 1. Coiled torsion spring 70 acts to bias pawls 77 and 78 to the normal positions thereof relatively to each other and to given normal positions with respect to the peripheries of wheels 37 and 49. Coiled compression spring 84 acts in the manner aforescribed to permit yieldable movement of either pawl 77 or 78 relatively to the other to insure against locking or binding of the same with respect to wheels 37 and 49 in the event of breakage or other failure of the main spring 53. By this means we insure the ability to positively rotate the driven shaft (and the drum

cylinder carried thereby), by the cooperative action of driving shaft 30, pins 60 and 62, pin 66^a or 66^b, and slot 65, either end wall of which is adapted to engage and positively drive pin 62 in the event of breakage of spring 53.

The aforescribed arrangement of parts is such that upon rotation of the driving shaft 30 in either direction from a given position to the next succeeding operative position the driven shaft will be moved with a snap action to a rotary position substantially exactly corresponding thereto. That is to say, no overtravel of the driving shaft is required to effect snap movement of the driven shaft to the position selected therefor by manual positioning of the usual operating handle. This feature is of great practical importance, especially when an indicating dial or legends are employed in conjunction with the manual operating means. In like manner it is obvious that if the handle of the driving shaft is manually released prior to complete movement thereof to its next succeeding rotary position, the torsion spring 53 will act automatically to effect return of said driving shaft to its last preceding position. Correct indication of the condition of the circuit or circuits controlled by the drum is therefore insured under all conditions.

We claim:

1. In an operating mechanism for a circuit controller, in combination, rotatable driving and driven shafts, a coiled torsion spring forming a driving connection between said shafts, means for effecting rotation of said driven shaft with a snap action from any one of a plurality of positions thereof to another, said last mentioned means comprising a latch wheel rigidly attached to said driven shaft and a pair of spring-biased pawls selectively cooperable with said latch wheel to temporarily lock the same pending storage of a given amount of energy in said torsion spring, a star wheel carried by said driving shaft and with respect to which the latter has a predetermined degree of lost motion upon rotation of said driving shaft in either direction, said star wheel coacting with each pawl when active to effect disengagement thereof from said latch wheel to effect snap movement of said driven shaft to another rotary position under the impulse of said torsion spring.

2. In an electric circuit controller, in combination, a rotatable driving shaft and a rotatable driven shaft, a coiled torsion spring affording a driving connection therebetween, a latch wheel rigidly attached to said driven shaft, a star wheel loosely mounted on said driving shaft adjacent and in parallel relationship to said latch wheel, means including a pin associated with said driving shaft and said spring to positively limit the degree of rotation of said driving shaft in either direction independently of said star wheel, a pair of spring-pressed pawls arranged to be selectively engaged by one of a pair of spaced shoulders formed on said latch wheel, according to the direction of rotation of said driving shaft, pending storage of a given amount of energy in said torsion spring, the edge portion of said star wheel underlying each of said pawls, whereby upon a given degree of positive movement of said star wheel by said driving shaft the active pawl is lifted from locking engagement with the cooperating shoulder on said latch wheel to permit a predetermined degree of rotary movement of the latter under the bias of said torsion spring, and said driven shaft having circuit controlling elements associated therewith.

3. In an operating mechanism for a circuit controller, in combination, rotatably mounted driving and driven shafts arranged in axial alignment, means including a coiled torsion spring interposed between said shafts for effecting rotation of said driven shaft from each of a plurality of positions thereof to another, said last mentioned means comprising a latch wheel fixed to said driven shaft, a pair of pivoted pawls having spring-biasing means common thereto, said pawls being selectively cooperable with said latch wheel to temporarily lock the same pending storage of a predetermined amount of energy in said torsion spring, a star wheel rotatably supported by said driving shaft, a pin carried by said driving shaft and having a predetermined degree of lost motion with respect to said star wheel, a second pin carried by said latch wheel and also having a predetermined degree of lost motion with respect to said star wheel, said torsion spring having integral extensions arranged on opposite sides of each of said pins and normally acting to maintain said wheels in a given rotary relationship to each other, said star wheel coacting with said pawls selectively, according to the direction of rotation of said driving shaft, to effect disengagement of the pawl from said latch wheel, whereby the energy stored in said torsion spring is released to effect movement of said driven shaft to its next succeeding position with a snap action, and the other pawl under such conditions cooperating with said latch wheel to positively limit the angular degree of rotary movement of said driven shaft.

4. In an operating mechanism for a circuit controller, in combination, rotatably mounted driving and driven shafts arranged in axial alignment, means including a coiled torsion spring interposed between said shafts for effecting rotation of said driven shaft from each of a plurality of positions thereof to another, said last mentioned means comprising a latch wheel fixed to said driven shaft, a pair of pivoted pawls having spring-biasing means common thereto, said pawls being selectively cooperable with said latch wheel to temporarily lock the same pending storage of a predetermined amount of energy in said torsion spring, a star wheel rotatably supported by said driving shaft, a pin carried by said driving shaft and having a predetermined degree of lost motion with respect to said star wheel, a second pin carried by said latch wheel and also having a predetermined degree of lost motion with respect to said star wheel, said torsion spring having integral extensions arranged on opposite sides of each of said pins and normally acting to maintain said wheels in a given rotary relationship to each other, said star wheel coacting with said pawls selectively, according to the direction of rotation of said driving shaft, to effect disengagement of the pawl from said latch wheel, whereby the energy stored in said torsion spring is released to effect movement of said driven shaft to its next succeeding position with a snap action, the other pawl under such conditions cooperating with said latch wheel to positively limit the angular degree of rotary movement of said driven shaft, and the spring-biasing means common to said pawls acting to return the same to their normal positions relatively to each other and to said star wheel and latch wheel after each snap movement of said driven shaft.

5. In an operating mechanism for a circuit controller, in combination, rotatably mounted driving and driven shafts arranged in axial alignment,

means including a coiled torsion spring interposed between said shafts for effecting rotation of said driven shaft from each of a plurality of positions thereof to another, said last mentioned means comprising a latch wheel fixed to said driven shaft, a pair of pivoted pawls having spring-biasing means common thereto, said pawls being selectively cooperable with said latch wheel to temporarily lock the same pending storage of a predetermined amount of energy in said torsion spring, a star wheel rotatably supported by said driving shaft, a pin carried by said driving shaft and having a predetermined degree of lost motion with respect to said star wheel, a second pin carried by said latch wheel and also having a predetermined degree of lost motion with respect to said star wheel, said torsion spring having integral extensions arranged on opposite sides of each of said pins and normally acting to maintain said wheels in a given rotary relationship to each other, said star wheel coacting with said pawls selectively, according to the direction of rotation of said driving shaft, to effect disengagement of the pawl from said latch wheel, whereby the energy stored in said torsion spring is released to effect movement of said driven shaft to its next succeeding position with a snap action, the other pawl under such conditions cooperating with said latch wheel to positively limit the angular degree of rotary movement of said driven shaft, the spring-biasing means common to said pawls acting to return the same to their normal positions relatively to each other and to said star wheel and latch wheel after each snap movement of said driven shaft, and said last mentioned spring-biasing means also acting, in the event of failure of said torsion spring, to permit forcible movement of said star wheel and said latch wheel relatively to either or both of said pawls, for the purpose set forth.

6. In a reversing snap action operating mechanism for a drum controller, in combination, rotatable driving and driven shafts arranged in axial alignment, means adapted upon a predetermined degree of rotary movement of said driving shaft in either direction to effect a corresponding degree of rotary movement of said driven shaft with a snap action, said means comprising a latch wheel rigidly attached to said driven shaft, a star wheel carried by said driving shaft and rotatable with respect thereto, said star wheel having an opening formed therein eccentric to the axis thereof, a pin attached to said latch wheel and extending with a predetermined amount of clearance through said star wheel opening, a second pin attached to and movable with said driving shaft in an arc parallel to said first mentioned pin, a coiled torsion spring surrounding said driving shaft and having end portions arranged to overlap opposite sides of said pins, means affording a lost motion driving connection between said second mentioned pin and said star wheel, means comprising a pair of hook-shaped pawls normally spring-biased to a given relationship to each other and to said latch wheel, said pawls acting selectively to temporarily lock said latch wheel against rotation in either direction pending storage of a given amount of energy in said torsion spring, and said star wheel acting in each instance to effect releasing movement of the active pawl, whereby said latch wheel and said driven shaft are moved with a snap action to the next succeeding position thereof, the other pawl acting in each in-

stance to positively limit the degree of said movement last mentioned.

7. In a reversing snap action operating mechanism for a drum controller, in combination, rotatable driving and driven shafts arranged in axial alinement, means adapted upon a predetermined degree of rotary movement of said driving shaft in either direction to effect a corresponding degree of rotary movement of said driven shaft with a snap action, said means comprising a latch wheel rigidly attached to said driven shaft, a star wheel carried by said driving shaft and rotatable with respect thereto, said star wheel having an opening formed therein eccentric to the axis thereof, a pin attached to said latch wheel and extending with a predetermined amount of clearance through said star wheel opening, a second pin attached to and movable with said driving shaft in an arc parallel to said first mentioned pin, a coiled torsion spring surrounding said driving shaft and having end portions arranged to overlap opposite sides of said pins, means affording a lost motion driving connection between said second mentioned pin and said star wheel, means comprising a pair of hook-shaped pawls normally spring-biased to a given relationship to each other and to said latch wheel, said pawls acting selectively to temporarily lock said latch wheel against rotation in either direction pending storage of a given amount of

15
20
25
30

energy in said torsion spring, said star wheel acting in each instance to effect releasing movement of the active pawl, whereby said latch wheel and said driven shaft are moved with a snap action to the next succeeding position thereof, the other pawl acting in each instance to positively limit the degree of said movement last mentioned, and the spring-biasing means associated with said pawls serving to prevent binding of said pawls with respect to said star wheel and said latch wheel in the event of failure of said torsion spring, to thereby render effective the aforementioned means affording a positive driving connection between said driving and driven shafts.
